UNITED STATES PATENT OFFICE.

WILLIAM SCHOTT AND WILLIAM EWER, OF FLINT, MICHIGAN.

CAR-REPLACER.

SPECIFICATION forming part of Letters Patent No. 738,632, dated September 8, 1903.

Application filed June 9, 1903. Serial No. 160,776. (No model.)

To all whom it may concern:

Be it known that we, WILLIAM SCHOTT and WILLIAM EWER, citizens of the United States, residing at Flint, in the county of Genesee and State of Michigan, have invented new and useful Improvements in Car-Replacers, of which the following is a specification.

This invention relates to improvements in car-replacers, and is of the type wherein two interchangeable companion devices are employed to simultaneously coact with the wheels.

The object of the invention is to provide a device which can be applied to a railroad-track in such a manner as to effectually insure a derailed wheel being replaced, the construction being arranged so that the wheel in riding up its guide toward the rail causes the replacers to hug closely and grip on the track.

20 A further object of the invention is to provide a pair of replacing devices which can be arranged to either replace a wheel on the right or left hand track, each replacer having exactly the same characteristics in every respect, except that the grooves are arranged on opposite sides of a medial line.

With these several objects in view we will describe the invention in detail and point out particularly in the claims the features which 30 are deemed novel.

In the drawings, Figure 1 is a top plan view illustrating a pair of wheels as having run off the right-hand side of the track and the replacers arranged to guide the wheels to the tracks. Fig. 2 is a similar view, but showing the wheels on the left of the tracks and the replacers arranged accordingly. Fig. 3 is a cross-section on the line 3 3, Fig. 1. Fig. 4 is a similar view on the line 4 4, Fig. 1. Fig. 40 5 is a vertical section of one of the replacers. Fig. 6 is a detail perspective view of a replacer.

The same characters refer to like parts in all the figures.

45 As both of the replacers are the same in construction, we will describe but one in detail.

The body of the replacer is indicated at 1, and its upper surface is inclined upwardly, 50 as at 1^a, toward the highest point, where a horizontal shelf 2 is formed, grooves 3 being formed in the under side for lightness. The

bottom of the body portion is flat and is provided at appropriate points with spurs 4 to bite into the ties to steady and hold the replacer when in use. The lowest point 6 of the surface 1^a is in close proximity with the top of the ties, and radiating from about the center thereof and diverging to about the opposite edges of the beginning of the shelf 2 are two grooves 7 and 8. The groove 8 extends across the shelf 2 at 9 to the outer end thereof, while groove 7 terminates at the commencement of said shelf. A third groove 10 begins approximately half-way between the edge of the surface 1 and groove 8, and runs in the same plane as the latter, and it merges into said groove 8 near its upper end, but before shelf 2 is reached. Located intermediate the grooves 7 and 8 is a V-shaped 70 guide 12, the front point 13 of which is elevated from the surface 1^a and from which it gradually rounds and tapers off to the surface just in advance of the shelf.

On the sides of the body portion 1 are formed overhanging lips 15 and 16, whose upper surfaces are slightly below the level of the shelf. Inasmuch as the upper surfaces of the lips 15 and 16 are horizontal and are nearly on a level with the top of the incline surface of body portion 1, obviously there will be deep vertical walls 17 and 18, which gradually taper away to nothing. The lips 15 and 16 have depending flanges 19, which fit over the rails, while longitudinal 85 ribs 21 are formed on the outside of the vertical walls 17 and 18 to fit the grooves in the sides of the rails.

The shelf 2 is an important part of our invention, and its construction is to be particularly emphasized. As stated, this shelf is at the upper end of the inclined surface 1^a, and it is only separated on one side from the upper surface of the lip 16 by the extended portion 9 of groove 8. The opposite edge of the shelf is rounded off at 27 and terminates on a line with the outer side of the vertical wall 17, and at the junction of the wall 17 and the shelf is a shallow groove 28. It will be observed, then, that the lip 15 terminates some little distance behind the front of the shelf, the object being to form a guide, as at 29, between the rail 30 and the rounded portion 27.

In operation, referring now to Fig. 1, the lip 15 of a replacer A is fitted over the rail 30, while the lip 16 of a second replacer is fitted over the companion rail 33. Supposing the wheels to have been derailed as shown in this figure, they are started forward, and they readily roll up the inclined surface, eventually finding their way—wheel C the groove 7 in replacer A and wheel D one or the other of the grooves 8 or 10 of replacer B. The wheel C will be directed toward the space 29, where its flange will roll therein and its tread will engage the rail 30, while the flange of wheel D will be carried by the groove 9 to the inside of rail 33, and when the end of shelf 2 is reached its tread will be in line with rail 33. Should the wheels be derailed as shown in Fig. 2, obviously the same operation takes place, except in a reverse manner, as will be readily understood.

A replacer thus constructed affords a device which when positioned to replace one pair of derailed wheels of a truck will not have to be removed to permit the passage of the companion set of wheels—that is to say, that the proportions of a replacer will be such that when the front pair of wheels, for instance, are replaced, the rear wheels will be about on the rear end of the replacer. Hence the latter cannot be well removed. However, we overcome this objection by making provision for the passage of the rear set of wheels in that they may pass over the surfaces of the lips 15 and 16, the flange of one wheel passing along in groove 28. The object of the guide 12, it will be understood, is to deflect a wheel toward the respective grooves.

From the foregoing description it is believed the construction and advantages of our invention will be readily comprehended by those skilled in the art to which it appertains.

What we claim as new is—

1. A car-replacer comprising a body portion having diverging grooves, a shelf at the upper end of said body portion, one of the grooves extending out and terminating at the end of said shelf while the other groove terminates at the beginning of the shelf, and lips on each side the body portion to adapt the replacer to either a right or left railroad-track, one side of the shelf terminating a short distance from

one of the lips to form a space adjacent a co-acting track, substantially as described.

2. The combination with a pair of wheel-replacers, each of which consists of a body portion having an inclined surface with grooves and a shelf, a lip on each side of the body portion, one of said lips terminating behind the shelf, while the other one extends to and terminates with the end of the shelf, one of the grooves terminating where the shelf and the flange behind it terminates, while the other groove extends out to and terminates with the outer end of the shelf, one lip of each replacer fitting over a respective railroad-track, for directing a flange of a wheel over a track and directing the flange of a companion wheel to a space inside of a track formed by the shelf terminating adjacent thereto, substantially as described.

3. A car-replacer comprising a body portion having two diverging grooves, a shelf, one of said grooves terminating at the beginning of the shelf while the other terminates at the outer end of the shelf, a third groove in a plane with and merging into the groove which terminates at the outer end of the shelf, a lip on each side the body portion for engaging a railroad-track, the lip adjacent the shelf terminating at the beginning of the latter, the edge of the shelf next the said lip being rounded to form a space between it and a track when the replacer is in use, substantially as described.

4. A car-wheel replacer comprising a body portion which has an inclined upper surface, a shelf formed at the upper end of said inclined upper surface, two diverging grooves in said inclined surface, a lip each side the body portion to engage a railroad-track, the upper planes of the lips being below and separated from the top of the shelf, and a guide on the inclined surface intermediate the grooves, substantially as described.

In testimony whereof we have signed our names to this specification in the presence of two subscribing witnesses.
